RAIL FOR A HIGHWAY BARRIER

Ted E. Thompson, Center Valley, Pa., assignor to Bethlehem Steel Corporation, a corporation of Delaware

Filed Sept. 30, 1968, Ser. No. 13,785

Term of patent 14 years

Int. Cl. D25—01

U.S. Cl. D28—1

FIG. 1

FIG. 2

FIG. 1 is a perspective view of a section of a rail for a highway barrier showing my design.

FIG. 2 is a cross-section view of the rail shown in FIG. 1.

I claim:

The ornamental design for a rail for a highway barrier, as shown.
